WIRE-WRAPPING MACHINE

Philip R. Hirsh, Montclair, N. J., assignor to
 Lock Joint Pipe Company, East Orange, N. J.,
 a corporation of New Jersey

Application August 18, 1944, Serial No. 550,122

11 Claims. (Cl. 242—7)

1

This invention relates to the construction of tanks, standpipes, large diameter pipes and like structures and more particularly to machines for applying tensioned windings about such structures.

Among the objects of the invention is to effect economies in the construction of tanks and other objects made from material such as concrete which, except for externally applied reinforcing, would have a low bursting strength.

Another object of the invention is to provide a wire wrapping machine capable of governing tension in a wire during a winding operation so as to enable maximum utilization of the strength of a given wire, and the application of a predetermined tension whereby selection of a suitable wire may be made in the interest of avoiding such waste of material as would otherwise result by the employment of a wire having strength greater than required and by applying the wire under an unknown tension. Another object of the invention is to provide a wire wrapping machine capable of wrapping wire uniformly under a predetermined amount of tension so as to enable utilization of the well known principle of pre-stressing for the purpose of economy in reinforcing steel and improved functioning of the structure.

The machine of the present invention is capable of exerting any desired tension in a wire and of maintaining such tension during a wire winding operation in which the wire is laid about an object, such as a tank, standpipe, or large diameter pipe. The wire winding and stressing machine is caused to travel over the surface of an object by cooperating mechanisms which traverse the machine about the object and at the same time advance it longitudinally of the axis of the object. The travel of the machine circumferentially of the object and longitudinally of the object is subject to control so that the speed of application of the wire and the pitch of the wire being applied are capable of variation with respect to each other whereby different requirements of construction may be readily met. The machine is capable of use for the construction and reinforcing of tanks and other containers designed for containing liquids and materials having different static heads and containers having different heights. Other uses of the invention will be apparent from the herein contained description of a form of machine; for example, a tensioned wrapping can be applied thereby about solid objects, such as concrete columns and piles.

Further and other objects of the present in-

2

vention will be hereinafter set forth in the accompanying specification and claims and demonstrated by the drawings which show by way of illustration a preferred embodiment and the principle of my invention and what I now consider the best mode in which I have contemplated applying that principle. Other embodiments of the invention employing the same principle may be used and structural changes made as desired by those skilled in the art within the spirit of the appended claims and without departing from the present invention.

Referring to the drawings, Fig. 1 illustrates a front elevation of part of a machine embodying the principle of the invention;

Fig. 2 is a side elevation of the machine shown in Fig. 1 with its associated wire winding carriage in working position;

Fig. 3 is a top view of the machine shown in Fig. 2;

Fig. 4 is a front elevation of the wire winding carriage;

Fig. 5 is a horizontal sectional view of mechanism for changing the position of a guide sheave;

Fig. 6 is a section on line 6—6 of Fig. 5;

Fig. 7 is a schematic view illustrating the manner in which the wire and tension-applying cable is trained over sheaves; and

Figs. 8 and 9 are detail views of a wire clamp.

While the machine is suitable for applying wire about tanks, standpipes, large diameter pipes and other objects designed for various uses, and having walls of different strengths apart from the reinforcing provided by a tensioned winding, a particularly useful application of the invention is for affording economies in the construction of objects wherein the wall has but little tensile strength, such as, for example, a wall made of concrete or mortar and having as an integral part thereof but little or no steel reinforcing. Such objects may be molded or cast in place wholly by the employment of concrete, or they may be built up by the application of mortar by projecting devices. After the wall has been constructed, the wall is placed under compressive stress by the application of a tensioned wire winding against its exterior surface. The amount of compression in the material of a wall for maintaining the wall under compressive stress when the tank is filled, is predetermined, and the winding is applied under such tensile stress as will meet this condition. Consequently, it is important that the exact amount of pre-stressing required is determined. It also is a matter of considerable im-

portance that the maximum strength of available wire be made use of in order that the cost of materials are maintained at a minimum. In order that these objectives be attained, it is of ultimate importance that a machine be able to maintain the wire at required tensional strength to meet the specifications of a particular job.

An assembled machine is illustrated in the drawings. This includes a traverse control support or frame 10 (Fig. 1), an elevating platform or elevator 11 and wire winding mechanism 12 (Figs. 2 and 3). The machine is shown in an operating position opposite a tank 13. The illustrated tank may be any other kind of vertically standing object about which a tensioned wrapping is to be applied.

The support 10 is in the form of a skeleton box-like tower which is made up of structural steel members including four main columns of which the front pair 14 and 15 are shown in Fig. 1. The two columns at the back of the frame are similar to the front pair. The front and back pairs of these columns are connected, respectively, by head-beams 16 and 17 and by foot-beams 18 and 19. Head-beams 16 and 17 are connected at their ends by channel irons 20 and 21, and similar structural elements connect the foot-beams 18 and 19. Columns 14 and 15 are cross-braced by a suitable number of structural elements 22, 23 and 24, but the vertical expanse between head-beam 17 and the foot-beam at the back of the tower is open to provide for the vertical travel of elevating platform 11. The construction of support 10 thus far described is extended to the left and right (Fig. 1) by frames 25, 26, made up from structural elements which are rigidly secured to the main columns and thus constitute parts of the support. Sets of cross-braces 27 and 28, (Fig. 2) and other suitable connecting members 29, provide lateral rigidity to the support.

The support is provided with a pair of bolster blocks 30, 31, which carry bearings for pairs of truck wheels 32, 33, respectively. Each bolster block is pivoted about vertical axes 34, 35, respectively (Fig. 3), so that the bolster blocks can turn about these axes with respect to pairs of supporting sills 36, 37. These sills are parts of frames 25 and 26, respectively. Relative sliding movement between the bolster blocks and the over-lying sills is desired so as to enable the correct positioning of the trucks on radial lines of any particular tank which is to be wound with wire. The trucks 32 and 33 run on rails 39, 40 which are concentrically placed with respect to the wall of the tank.

During a wire winding operation the support or tower travels on the rails around the tank and causes the wire winding mechanism to wrap wire around the tank. The drive for traversing the complete machine may consist of a source of motive power mounted anywhere on the machine. A convenient location for the driving motor is shown at 42 (Fig. 3) at the lower part of the supporting tower. It is sufficient to provide power for driving one wheel of each of the pairs of truck wheels 32 and 33. Shaft 43 for one of the truck wheels 33 is driven from a variable speed transmission 44, (Figs. 1, 2 and 3) through the intermediary of a pair of bevel gears 45, vertical shaft 35 and a pair of bevel gears 47, one of which is keyed to truck wheel shaft 43. The bevel gears 45 receive their drive from the output shaft of variable speed transmission

44, which is in turn driven from motor 42 through a chain or belt and sprocket connection 43.

The power drive to one of truck wheels 32 is obtained from vertical shaft 35 through a chain and sprocket connection 50, including a sprocket wheel 51 on vertical shaft 34. A pair of bevel gears 52 transmit the rotation of vertical shaft 34 to shaft 53 by which one of the wheels of the pair of truck wheels 32 is driven. It is apparent that the speed of travel of the supporting tower about the tank may be regulated by changing the adjustment of the variable speed transmission 44. If the motor for traversing the machine about the tank is mounted on the elevating platform 11, or on the wire winding mechanism 12, and is arranged to drive the rollers 114 and 115 of the wire winding mechanism which bear against the exterior of the tank as described hereinafter, then the driving connections from motor 42 to the truck wheels 32 and 33 may be dispensed with, if desired. Should two traversing drives be used, the motors for each drive preferably would be synchronized so that each would exert the same driving influence for traversing the machine.

The elevating platform 11 includes a pair of stringers 55, 56, which are connected at their ends by I-beams 57, 58, to form a rectangular frame (Figs. 1 and 2). The I-beams extend beyond stringer 56 in cantilever fashion for supporting the winding mechanism carriage opposite the tank wall, as illustrated in Fig. 2. The I-beams carry rails 59, 60 which provide support for guiding the wire winding mechanism so that the same may determine its own position with respect to the supporting tower and platform. The platform may be boarded over with planks 61 for the convenience of the operator. The end of the platform remote from the tank is provided with a counterweight 62 for counterbalancing the eccentric weight of the wire winding mechanism.

Between the front and back pairs of columns of the tower, opposite column 14 and column 15, respectively, there is a vertically extending guide rail 63 and a similar vertical guide rail 64 (Fig. 3). These two vertical guide rails are secured to the tower and extend from its foot to its head-beams. Guide rail 63 is engaged on opposite sides by a pair of rollers or guide blocks 65 which are carried by the elevating platform 11. A similar pair of rollers or guide blocks 66 engage opposite sides of vertical guide rail 64.

The platform 11 is supported, and its rising and lowering movements are controlled, by pairs of chains at each end of the platform. Chain 70, at the right side of Fig. 1, has its ends connected to stringer 55 at 71. Its companion chain 72, at the same side of the tower, has its ends connected to stringer 56 at 73 (Fig. 2).

The upper extent of sprocket chain 70 passes over a single sprocket 73, and the lower extent of the chain passes over another single sprocket 74. Chain 70 also is engaged by idler sprockets 75, 76 and a driven sprocket 77 on countershaft 78. It will thus be seen that rotation of the countershaft 78 in either direction will cause the right end of stringer 55 (Fig. 1) to rise or lower, as the case may be.

A similar arrangement of idler and driven sprockets is provided for engaging the companion sprocket chain 72 to enable corresponding movements of the right end of stringer 56 through operation of countershaft 78. As shown in Fig. 2, upper and lower single sprockets 79, 80,

idler sprockets 81, 82 and driven sprocket 83 are mounted in the frame for guiding and actuating sprocket chain 72. Driven sprockets 77 and 83 are carried by countershaft 78 which has a driving sprocket and chain connection 84. This driving sprocket and chain connection 84 is driven from a speed reducer 85.

Speed reducer 85 is directly connected to the power shaft 86 of variable speed transmission 44 so that its driving effect on the countershaft is directly proportional to the speed of motor 42 which is directly connected to shaft 86. Since the drive for the traverse of the tower about a tank is derived through the power output shaft 87 of the variable speed transmission 44, it is apparent that flexibility is provided for varying the rate of travel of the machine about the tank with respect to the elevating rate of the wire winding mechanism and its platform 11. By varying the rate of circumferential travel of the machine with respect to the elevating rate of the platform, the resultant direction of the movement of the wire winding mechanism over the surface of the tank can be controlled whereby the pitch of the wire wrapping may be varied at will.

The left end of the platform (Fig. 1) is supported, and its rising and lowering movements are controlled through a pair of similarly mounted chains, one of which is shown at 88 in Fig. 1. These chains are operable together and at the same rate as chains 70 and 72 during vertical travel of the platform. Chain 88 is connected to the left end of stringer 55 at 89 (Fig. 1). Its upper end is trained over a double sprocket 90 and its lower end is trained over a single sprocket 91. Double sprocket 90 is engaged by an endless chain 92 which engages the single sprocket 93 and is driven thereby. Sprocket 93 is driven through gears 94, 95, the latter of which is keyed to the same shaft to which sprocket 73 is keyed. It is thus apparent that the two ends of stringer 55 will be caused to rise and lower at the same time and at the same rate, the drive for chain 88 being derived through chain 92 and chain 70 from the countershaft 78. A chain companion to chain 88 is attached to the left end of stringer 56 and it is operated simultaneously therewith from countershaft 78 through chain and sprocket connections located at the back of the tower which are similar to those described for operating chain 88. It is thus apparent that similar elevating and depressing movements are simultaneously imparted to both ends of platform 11.

For lowering the platform, the drive between the power shaft 86 and the output power shaft 87 of the variable speed transmission 44 can be discontinued and the motor 42 driven in the reverse direction, or a reverse gear mechanism may be interposed between the motor and variable speed mechanism shaft 86.

Wire winding mechanism

The wire winding mechanism carriage includes a box frame having a lower rectangular frame 100 and an upper rectangular frame 101 connected together by a number of standards such as 102, 103 (Fig. 2). The upper and lower rectangular frames and the standards may be formed from structural elements such as channel irons or angle irons and as illustrated in the drawings. The box frame is mounted upon and fastened to a supporting rectangular frame 105 (Figs. 2 and 4). Brackets 106, 107 are attached to the frame and carry bearings for roller shafts

108, 109. Shaft 108 has at its ends rollers 110 and 111 and shaft 109 also has at its ends similar rollers, one of which is shown at 113 (Fig. 2). The left hand rollers (Fig. 1) bear upon rail 59 and rollers 111 and 113 bear upon rail 60. These rails rest, respectively, upon beams 57 and 58 of the platform so that the carriage may be moved horizontally to and from the tower and float between the tower and the tank during a wire winding operation.

For providing a wheeled contact between the carriage and the tank as the machine travels about the tank there are provided two pairs of rollers 114, 115, mounted, respectively, on vertical shafts 116, 117 (Figs. 3 and 4). The shafts are attached to bearings supported by the box frame of the carriage.

The function of the wire winding mechanism is to enable the winding of a wire under tension about a tank, standpipe or a large diameter pipe. A number of sheaves are provided for guiding the wire during a winding operation and for cooperation with a tensioning device designed for maintaining the wire under a predetermined tension as it is being applied to the object. While the arrangement of the sheaves may be changed so as to enable the winding of wire in either direction about an object, I find it convenient to describe the wire winding mechanism as arranged for applying a wire in a clockwise direction as seen from above.

In Fig. 7 I have illustrated the course of the wire through the winding and tensioning mechanism. The wire 113 is supplied from a spool 119 which is mounted upon a bracket 120 on the carriage. The bracket has a spindle about which the spool may rotate as the wire is drawn from it. In threading the wire through the wire winding mechanism it is drawn over sheave 121 and then passes around the object one or more times and then passes over sheave 122 at the other end of the winding mechanism (Fig. 7). The one or more turns about the object are in advance of the final turns of wire which remain on the object as a permanent part of its construction. In many cases one turn of the wire will suffice but more can be made in order to assure frictional resistance between spool 119 and the portion of the wire 123 which comes to the winding mechanism after it encircles the object.

After passing over sheave 122 the wire passes successively over sheaves 124 and 125, each of which is free to rotate on a fixed shaft. The wire then passes over floating sheave 126 and sheaves 127, 128, and 129, which are free to rotate. Shafts of sheaves 121, 122, 124, 125, 127, 128 and 129 are carried upon brackets extending from structural elements of the carriage. These seven sheaves are idlers for changing the direction of the wire. The positions of sheave 122 and of sheaves 121 and 129 are adjustable for purposes hereinafter described.

Upon leaving sheave 128 the wire passes over sheave 129 and its end is anchored at 130, which is the starting point for the permanent winding. This ordinarily would be located at the lowest point of an object to which wire reinforcing is to be applied, as shown in Fig. 2. The anchor is a fixed member solidly attached to the exterior of the object. Tension is applied to the wire by the application of force to the floating sheave 126.

When the machine is first threaded, sheave 126 is at its most right-hand position, just to the left of sheave 125 (Fig. 7), and a loop of the wire

is engaged thereby. The loop is intermediate separated windings, the temporary advance winding and the final permanent winding. Force is applied to sheave 126 through a cable 131 which is attached to a yoke 132. This yoke is suspended from a trolley 133 which carries the yoke and shaft upon which sheave 126 is mounted, the arms of the yoke serving to support the end of the shaft at either side of the sheave. Trolley 133 is provided with a pair of rollers which bear upon the flanges of an H-shaped beam structure 134. Beam structure 134 is fixed to and is carried by the wire winding carriage and it serves to support the wire tensioning mechanism 135 (Figs. 7, 3 and 4). Upon the left end of beam structure 134 there is mounted a freely rotatable guide sheave 138 over which cable 131 passes.

The wire tensioning mechanism illustrated comprises a weighing beam 140 pivotally mounted at 141 and carrying at its free end a winch 142 which is driven by motor 143. The cable attached to yoke 132 and passing over sheave 138 extends to winch 142 to which it is attached. In the operation of the wire tensioning device, the weighing beam 140 floats between contacts 145 and 146 which operate a limit switch 147 by which the operation of the motor is controlled. The weighing beam 140 maintains cable 131 in tension and the amount of tension can be varied by changing the load applied on the weighing beam. As the wire is wound about the object, it is extended in length as the result of the tension applied thereto through sheave 126 and this extension is taken up by the permissible movement of sheave 126 between sheave 125 and sheave 128 at the end of beam structure 134. In travelling from its extreme right-hand position to its extreme left-hand position, as shown in Fig. 7, cable 131 is maintained taut while at the same time it is being taken up by winch 142 under the operation of the motor 143, which is started when contact 145 operates switch 147 as the weighing beam drops. The operation of the motor is discontinued when weighing beam 140 rises sufficiently to cause contact 146 to operate switch 147 and break the motor connection.

When a wire winding operation has proceeded to such an extent that sheave 126 has reached the end of its travel, it becomes necessary to stop the winding operation so as to place sheave 126 at its starting position just to the left of sheave 125. The operation of the machine is discontinued for this purpose and wire 118 is temporarily clamped to the frame of the carriage by clamps 150, 151 which are secured to brackets 152 and 153, respectively. By these clamping means, the wire permanently wound about the object and which comes to the carriage over sheave 129, and the portion of the wire which comes to the carriage over sheave 122 can be held without loss of tension so that the operation of the wire tensioning device 135 may be temporarily discontinued. Upon effecting this clamping, and the release of tension in cable 131, sheave 126 can be moved to its starting position at the left of sheave 125, a section of wire of the loop of wire between the clamps removed, and the cut end of one of the reaches of the wire threaded over sheave 126 and then spliced to the cut end of the other reach of wire. For splicing the cut ends of the wire together I prefer to use a sleeve connector which is fastened to the wires by compression thereupon and frictionally engages both ends.

After the wire has been spliced, the operating tension may be reapplied to the wire by exerting the proper amount of pull on cable 131 by causing operation of the tension applying mechanism 135. Thereafter the clamping effect of clamps 150 and 151 on the spliced wire is removed and the machine is ready for continuing the winding operation under the same conditions of tension that prevailed before making the splice. When the supply of wire from spool 119 is exhausted, the empty spool may be replaced by a filled spool and its wire spliced to the end of the wire temporarily encircling the tank between sheaves 121 and 122.

Clamp 150 also may be used temporarily as a brake on the wire when the machine is being set up to provide sufficient frictional hold on the object by the wrapping between spool 119 and sheave 122 to resist the load to be applied by the tensioning mechanism.

Guide sheaves 121, 129 and 122 may be mounted on permanently positioned shafts but I prefer to mount them on supports which will permit their positions to be adjusted vertically to enable the wire winding machine to start wrapping an object at its bottom and to end the wrapping at its top. As shown in the drawings, particularly in Figs. 2 and 4, the positions of these sheaves are close to the lower part of the carriage and in this position the beginning of the wrapping can start at the bottom of the object, as shown in Fig. 2. Except for the last turns at the top of the object, these sheaves may remain, if desired, in the positions illustrated in the drawings, but in order to complete the winding of the object at its top end, provision is made for moving the sheaves to the upper portion of the carriage. This is desirable because the exterior of the object laterally supports the carriage by reason of the pressure exerted by the tensioned wire on the carriage and rollers 114 and 115. Sheaves 121 and 129 are supported and moved similarly to sheave 122 and it will suffice to explain the operating and supporting structure for the latter sheave.

Sheave 122, Figs. 3, 4, 5, 6 and 7, is supported on a stud shaft 156 which is carried by a slide 157. Parallel rails 158 and 159 are provided for guiding the slide. The slides are fastened to a plate 161 which is secured to the carriage. The slide has fastened to it the ends of an endless chain 162 which passes over sprocket wheels 163, 164 carried by plate 161. Sprocket wheel 163 is keyed to a shaft carrying a worm wheel 165 which is engaged by a worm 166. The shaft of worm 166 is connected to a shaft 167 having hand wheels 168, 169 which are readily accessible to an operator. The mechanism for adjusting the position of the sheaves 121 and 129 along guide rails 170, 171 at the other end of the carriage is arranged and constructed similarly to that for adjusting the position of sheave 122, and its worm wheel shaft is similarly connected to hand wheel shaft 167. The worm gears and worms are of the self-locking type whereby the sheaves are held in any set position.

It is apparent from the description of operation of the mechanism for changing the positions of sheaves 121, 122 and 129 that the spacing of the wrappings of wire about the object can be changed independently of any change in the elevation of platform 11. This may be accomplished under manual control by

having an operator gradually lift the sheaves by turning one of the hand wheels 168, 169 as the tower is traversing about the object. The upper limit of movement of the sheaves, with respect to the carriage, need be sufficient only to permit winding to a point just above the uppermost rollers 114, 115 by which the carriage is supported against the object under the influence of the tensioned wrapping.

When the last turn of wire has been laid 10 against the object, the machine is stopped and the wire is securely fastened to an anchor fixed to the object. When the wire is secured, the tension on the wire is released and the end of the wire beyond the anchor is cut.

If it should be considered desirable, turns of wire about the object may be occasionally anchored to members fixed in the wall of the object, but this practice is not deemed indispensable because the present invention enables the tensioning of wire about an object within desired limits which are carefully computed beforehand and therefore are known to be below the maximum breaking strength of the wire.

What is claimed is:

1. A machine for applying wire about a tank or like stationary object, comprising a structure having a vertical height at least as high as an object about which a wire is to be wrapped, a track for guiding said structure about said object, means including wheels supporting said structure on said track, a wire-wrapping mechanism, means carried by said structure of elevating said wire-wrapping mechanism, and means for advancing said structure over said track, said last-named means including a motor and connections from said motor to said wheels for driving said wheels to propel said wire-winding mechanism by advancement of said structure.

2. A machine for applying wire about a tank or like stationary object, comprising a structure having a vertical height at least as high as an object about which a wire is to be wrapped, a track for guiding said structure about said object, means including wheels supporting said structure on said track, an elevator, means carried by said structure for guiding said elevator for vertical travel, means for actuating said elevator along said guiding means, and means for actuating said structure over its track, said last-named means including a motor and connections from said motor to said wheels for driving said wheels to propel said elevator about said object by movement of said structure over said track.

3. A machine for applying a wire about a tank or like stationary object, comprising a structure adapted to travel in a path concentric to the object, an elevator carried thereby, means on said structure for guiding said elevator opposite the surface of said object, a track carried by said elevator and extending normal to the surface of the object, a carriage mounted on said track, a wire-wrapping mechanism on said carriage, and rollers carried by said carriage for engaging the surface of said object during a wire winding operation.

4. In a machine for wrapping a wire about an object, the combination comprising a carriage having sheaves adapted to engage a loop of wire with reaches which extend between the sheaves and opposite sides of an object, means including a cable attached to one of said sheaves whereby tension may be applied to said loop of wire, guide sheaves for said reaches of wire, adjustable supports on said carriage for said guide sheaves, and

actuatable means for changing the positions of said adjustable supports on said carriage while tension is maintained in said wire whereby the locations of said reaches of wire may be changed with respect to said carriage.

5. In a machine for wrapping a wire about an object, the combination comprising a carriage having sheaves adapted to engage a loop of wire with reaches which extend between the sheaves and opposite sides of an object, all of said sheaves being idlers providing for the free running there-over of said wire and the training of said wire through said carriage, a platform, means having connection with said platform and said carriage for enabling movement of the carriage laterally of itself, rollers on said carriage for providing support for the carriage against an object to be wrapped with wire and travel of the carriage over the surface of said object, the axes of said rollers being at substantially right angles to the permissible direction of movement of said carriage on said means, and means separate from said sheaves and said wire for causing said carriage to travel on said rollers during a wire-wrapping operation, said last-named means being operatively connected to said platform to move said platform and said carriage in a direction perpendicular to the axes of said rollers and about said object.

6. In a machine for wrapping a wire about an object, the combination comprising a carriage adapted for relative movement with respect to the surface of a body to be wrapped with wire, means carried by said carriage for engaging a loop of wire having reaches which constitute extensions from separated windings of the line about the object, said means including an idler sheave engaging said loop of wire, said loop of wire and reaches being an intermediate portion of a wire wrapped about said object, means for exerting force on said sheave for applying tension to said loop of wire, tension-applying means carried by said carriage and attached to said force-exerting means, rollers carried by said carriage for supporting said carriage in rolling contact with the surface of said object, and means separate from said loop-engaging means and said wire for advancing said carriage over the surface of said object, whereby said carriage is advanced about said object while tension is imparted to said wire by said force-exerting means.

7. A machine for applying wire about an object, comprising a carriage, a wire-wrapping mechanism carried by said carriage, said wire-wrapping mechanism including sheaves for engaging a loop of wire formed by continuations from separated windings about the object, said loop of wire and continuations constituting an intermediate portion of a wire wrapped about

60 said object, means carried by said carriage for applying tension in said loop of wire, means cooperating with said carriage and bearing against the surface of said object for wholly supporting said carriage during a wire-wrapping operation, and means separate from said tension-applying

65 means and said wire to traverse said carriage over the surface of said object during a wire-wrapping operation, said last-named means being driven independently of the tension in said

70 loop of wire.

8. A machine for applying a wire about a tank or like stationary object, comprising a structure adapted to travel in a path concentric to a tank, an elevator mounted on said structure, means for 75 moving and guiding said elevator vertically in re-

spect to said structure, a wire-wrapping mechanism carried by said elevator, said wire-wrapping mechanism including a linearly movable idler sheave for engaging a loop of wire formed by continuations from separated windings about the tank and for placing equal stress in said continuations and tensioning means for applying force on said idler sheave to tension and enlarge said loop of wire and tension said continuations equally, guide means between said wire-wrapping mechanism and elevator for enabling said wire-wrapping mechanism to move radially with respect to the tank whereby the tension applied to said loop of wire forces said wire-wrapping mechanism towards the surface of the tank, wheels carried by said wire-wrapping mechanism and bearing against the tank, and means separate from said wire-wrapping mechanism for actuating said structure horizontally about the tank and said elevator vertically with respect to the horizontal motion of said structure to direct said wire-wrapping mechanism in a helical path about the tank.

9. A machine for applying a tensioned wrapping of wire about a tank or like stationary object, comprising a travelling carriage mounted on rollers to bear against a tank, means on said carriage for guiding relatively loose wire from the rear of said carriage and into a temporary advance wrapping about said tank, means on said carriage for guiding the wire from the other end of the temporary advance wrapping onto the front of said carriage, means on said carriage for guiding the continuation of said temporary advance wrapping into a permanent wrapping about said tank, said permanent wrapping beginning to the rear of said carriage, means intermediate said last two-mentioned guiding means for applying tension to the wire between said two wrappings as the wire travels from the front to the rear of said carriage and into the permanent wrapping as the carriage moves over said tank, a second carriage for supporting said first-named carriage alongside said tank, and means mounted on said second-named carriage for driving said second-named carriage for advancing said first-named carriage over the surface of said object, whereby loose wire is continually run into the temporary advance wrapping and is tensioned upon leaving that wrapping and entering the permanent wrapping as said first-named carriage is moved over the surface of the tank.

10. A machine for applying a tensioned wrapping of wire about a tank or like stationary object, comprising a travelling carriage mounted on rollers to bear against a tank, means on said carriage for guiding relatively loose wire from the rear of said carriage and into a temporary advance wrapping about said tank, means on said carriage for guiding the wire from the other end of the temporary advance wrapping onto the front of said carriage, means on said carriage for guiding the continuation of said temporary advance wrapping into a permanent wrapping about said tank, said permanent wrapping beginning from the rear of said carriage, means intermediate said last two-mentioned means for applying tension to the wire between said two

wrappings as the wire travels from the front to the rear of said carriage and into the permanent wrapping as the carriage moves over said tank, a second carriage mounted for travel in a path concentric with the surface of said tank, means on said second carriage for supporting said first-named carriage, said last-named means having provision for free motion of said first-named carriage in a direction normal to the surface of the tank with respect to said second-named carriage so as to support said second-named carriage on said rollers laterally against the tank, and means for driving said second-named carriage in a path concentric to the surface of the tank for advancing said first-named carriage during a wire-wrapping operation.

11. A machine for applying a tensioned wrapping of wire circumferentially about a tank or like stationary object, comprising a travelling carriage mounted on rollers to bear against the surface of a tank, means on said carriage for guiding relatively loose wire from the rear of said carriage and into a temporary advance wrapping about said tank, means on said carriage for guiding the wire from the other end of the temporary advance wrapping onto the front of said carriage, means on said carriage for guiding the continuation of said temporary advance wrapping into a permanent wrapping about said tank, said permanent wrapping beginning to the rear of said carriage, means intermediate said last two-mentioned guiding means for applying tension to the wire between said two wrappings as the wire travels from the front to the rear of said carriage and into the permanent wrapping as the carriage moves over said tank, means for advancing said carriage in a helical path over the surface of said tank, and manually operable means for changing the locations of said three wire-guiding means laterally of the cross-wise motion of said carriage whereby the pitch of the helical wrapping may be varied at will without interrupting the travel of said carriage, said manually adjustable means including rails extending cross-wise of the front and rear direction of said carriage, blocks slideable on said rails and supporting said wire-guiding means, and gearing whereby said blocks may be moved to different positions lengthwise of said rails.

Certificate of Correction

Patent No. 2,520,402

August 29, 1950

PHILIP R. HIRSH

It is hereby certified that error appears in the printed specification of the above numbered patent requiring correction as follows:

Column 8, line 74, for "elevaton" read *elevation*; column 9, line 33, for the word "of" read *for*;

and that the said Letters Patent should be read as corrected above, so that the same may conform to the record of the case in the Patent Office.

Signed and sealed this 14th day of November, A. D. 1950.

[SEAL]

THOMAS F. MURPHY,
Assistant Commissioner of Patents.
